UNITED STATES PATENT OFFICE

158,066

DESK CABINET

Ruth Gerth, San Francisco, Calif.

Application November 15, 1947, Serial No. 142,562

Term of patent 14 years

(Cl. D33—19)

To all whom it may concern:

Be it known that I, Ruth Gerth, also known as Ruth Gerth Kosmak, a citizen of the United States, residing at 985 Union Street, in the city and county of San Francisco, and State of California, United States of America, have invented a new, original, and ornamental Design for Desk Cabinet, of which the following is a specification, reference being had to the accompanying drawing, forming part thereof.

I claim:

The ornamental design for a desk cabinet, substantially as shown.

RUTH GERTH.
